UNITED STATES PATENT OFFICE.

BRUNO VON BÜLTZINGSLÖWEN, OF NEW YORK, N. Y.

ADVERTISING SIGN.

Application filed May 11, 1922. Serial No. 560,104.

To all whom it may concern:

Be it known that I, BRUNO V. BÜLTZINGSLÖWEN, a citizen of the United States of America, residing at New York, in the 5 county of Bronx and State of New York, have invented certain new and useful Improvements in Advertising Signs, of which the following is a specification.

The present invention relates to advertising signs and has for its object to provide a simplified and comparatively cheap construction in which individual letters, numerals or other characters can at will be arranged, rearranged or exchanged and the 15 light or color effect of the individual characters and of the frame itself easily and quickly changed.

With this and other objects in view my invention consists in the construction, combination and arrangement of parts as will be hereinafter fully described and defined in the appended claims.

In the accompanying drawings in which similar reference characters denote corresponding parts, Fig. 1 is a front view of my new sign; Fig. 2 a longitudinal section on line 2—2 of Fig. 1; Fig. 3 a cross section on line 3—3 of Fig. 1; Fig. 4 an enlarged view similar to that of Fig. 1 of a part of the 20 sign, showing the letters or characters removed and the marginal compartments open; Fig. 5 is an enlarged section similar to Fig. 3 of a part of the frame; Fig. 6 is an enlarged section on line 6—6 of Fig. 4; Fig. 7 is a front view of an individual character frame; Fig. 8 a side view thereof and Fig. 9 a slightly modified construction of a 25 door and means for its attachment to a marginal compartment of the sign.

The sign according to this invention comprises a box shaped frame 10 preferably made of metal and the back wall 10', top 10², bottom 10³ and side walls 10⁴ of which are formed of a single piece. The said frame is open in front and the interior thereof has horizontal partitions 11, one near the top and one near the bottom to form longitudinal border compartments and a plurality of intermediate horizontal 30 partitions 12 dividing the space between the upper and lower border compartments into a number of character display compartments. Near each side of and inside the frame there is also a vertical partition 13 35 forming lateral vertical border compart-

ments. Riveted or otherwise fixed transversely to the inner face of the back wall of the frame are re-inforcing strips 14 and bearing on said strips is a reflector sheet or plate 16. The several partitions 11, 12 and 13, the rear edges of which are adapted to bear on the front face of the reflector plate are fixed to the walls of the frame by angle irons 17. Each of the horizontal partitions 11 is in front bent vertically toward the respective marginal wall of the frame as at 11', and then horizontally as at 11², while each intermediate partition 12 in front is bent vertically downward as at 12' then horizontally as at 12², then again vertically as at 12³ and finally inwardly and horizontally as at 12⁴, the vertical bends 11' and 12' being in alinement with one another. By the bends of said partitions 11, 12 grooves or bearings are formed for the character 40 frames 18 to be hereinafter described. Fixed to the lower face of the horizontal bend 12² of each partition 12 is an angle bar 19, the vertical part 19' of which extends downwardly in alinement with the vertical bend 12⁴ of said partition. The vertical bends 11', 12' and 19' serve as shoulders against which the upper parts of the rear walls of the character frames 18 are adapted to bear when inserted into the afore- 45 named grooves or bearings. The horizontal bends 12⁴ of each partition 12 serve as a front abutment for the upper end of the front wall of the character frame 18. The upper and lower border compartments are 50 adapted to be closed by swinging doors 20, which may be hinged or otherwise pivotally joined to the upper and lower walls 10², 10³ respectively of the frame 10, as at 21. The upper of these doors have the lower edges 55 bent horizontally inwardly as at 20' to form abutments for the front upper parts of the character frames 18 located in the respective uppermost and lowermost character compartments, while in the intermediate 60 character compartments the front upper parts of said frame 18 are held by the inner edges of the bends 12⁴ as already stated.

To form abutments for the lower front parts of the character frames 18 a longitudinal swinging angle bar or ledge 22 is provided for each character compartment, said angle bars being hinged at 22' or otherwise pivotally joined to the front ends of the partitions 12 and the lower partition 11, 110

the horizontal bends 22² of said angle bars being adapted in operative position to extend inwardly and bear with their inner edges against the front lower part of the 5 character frames.

The lateral border compartments may be closed by vertical swinging doors 23 hinged at 23' or otherwise pivotally joined to the frame 10 to swing horizontally.

10 Instead of fixing the doors 20 and 23 to the frame 10, the same may be made detachable, as for instance, through the medium of bayonet locking means 24, shown in Fig. 9, in order to enable the changing of 15 the doors when different patterns are desired.

In the border compartments are provided means for the attachment of lighting fixtures, such as electric bulbs 25. The doors

20 20 and 23 may have openings 26 to be covered from the inside by colored plates 27 of glass or the like. To allow the exchange of 25 the colored plates there may be secured to the inner face of each door below and above each opening 26 a grooved cross piece 28 to removably support said colored plate 27.

Likewise inside of each character compartment behind the channelled parts receiving the character plate 18, suitable fixtures such as sockets 29 for electric bulbs or other lighting means are provided.

The character frames 18 are hollow and rectangular in shape and have their rear walls 18', somewhat laterally displaced relative to their front walls 18², as shown in Fig. 7, so that when assembled in any one of the character compartments contiguous characters will laterally overlap one another and thus be held in alignment. These character frames have openings 18³ stamped or cut out in the front and rear walls conforming with the contour of a character and accommodate between said walls colored plates 18⁴, which are adapted to be inserted into 45 the same from the side through a slot 18⁵ substantially as described in my separate application of even filing date.

For locking the swinging doors 20 and 23 and swinging angle bars or ledges 22 in closed position, fingers 30 suitably pivoted to the frame are provided.

What I claim is:—

1. A sign frame of the character described, divided by partitions into character display compartments and lighting border compartments, swinging doors for said border compartments, the partitions forming the horizontal border compartments having bent portions to serve as rear abutments for the characters contained in the adjacent character compartments, and means for holding said characters in position.

2. The combination with individual removable characters, of a sign frame divided

by partitions into character display compartments, each of said partitions being stepped so as to form a rear portion to serve as a support for a lamp fixture, a shoulder to serve as a rear abutment for said characters and a base to support said characters and means for holding said characters in position thereon.

3. The combination with individual removable characters, a sign frame divided by partitions into character display compartments, each of said partitions being stepped so as to form a rear portion to serve as a support for a lamp fixture, a shoulder to serve as a rear abutment for said characters and a base to support said characters, and swinging angular ledges the horizontal portions of which when in operative position form front abutments for said characters.

4. A sign frame of the character described, divided by partitions into character display compartments and lighting border compartments, swinging doors for said border compartments, the partitions forming the compartments, having bent portions to serve as rear abutments for the characters contained in the adjacent character compartments the upper horizontal swinging door having a bend to serve as a front abutment for the characters in the upper display compartments, swinging angular ledges to act as front abutments for the characters in the other display compartments, and tilttable members for fixing said ledges in operative position.

5. In a box shaped sign frame having tiers of removable characters and a hollow border around all sides of said frame to form lighting compartments, a removable swinging door for each of said compartments having openings, means for attaching lighting fixtures in said border compartments, and means for removably supporting light modifying plates behind said openings, the upper horizontal swinging door being formed at its free end with a bend to serve as an abutment for the adjacent tier of characters.

6. In a box shaped frame having tiers of removable characters and a hollow border around all sides of said frame to form lighting compartments, a removable swinging door for each of said compartments having openings, means for attaching lighting fixtures in said border compartments and grooved members on the inner face of said doors for removably supporting light modifying plates covering said openings, the upper horizontal swinging door being formed at its free end with a bend to serve as an abutment for the adjacent tier of characters.

7. In a box shaped sign frame, having a hollow border around all sides of said frame to form lighting compartments, a reflector

extending over the entire inner face of the rear wall of said frame, partitions bearing against said reflector dividing said frame into a plurality of character compartments, 5 means on said partitions for attaching lighting fixtures, the forward ends of said partitions being shaped to form bases and rear abutments for characters and movable means carried by the front edges of said partitions to form front abutments for said characters. 10 In testimony whereof I affix my signature in presence of two witnesses.
